UNITED STATES PATENT OFFICE.

NEM WILLIAM BRANNON, OF GREER, SOUTH CAROLINA, ASSIGNOR TO DRAPER CORPORATION, OF HOPEDALE, MASSACHUSETTS, A CORPORATION OF MAINE.

THREAD-CUTTING TEMPLE.

Application filed June 19, 1925. Serial No. 38,352.

To whom it may concern:

Be it known that I, NEM WILLIAM BRANNON, a citizen of the United States, and a resident of Greer, county of Greenville, State of South Carolina, have invented an Improvement in Thread-Cutting Temples, illustrated in Figs. 1 and 2, and Fig. 4 is a view in perspective of the fixed cutter member.

5 The thread cutting temple of the type illustrated comprises a stand 1, mounted on some fixed part of the loom, such as the breast beam, and a shank 2 which slides yieldingly in the stand and terminates at its rearward end in the head portion where

10 are located the operative parts of the temple. These temples are located at both sides of the loom and are consequently right and left-handed, the one illustrated being that 15 located at the right hand side of the loom.

This invention relates to a thread cutting temple for looms such as is commonly employed for severing the filling ends close to the selvage which are left extending therefrom during the weaving operation.

The invention relates to that type of thread cutting temple in which the cutting mechanism comprises a fixed cutter member and a movable cutter member which cooperates to effect the severing action.

20 The object of the invention is to provide a novel form of fixed cutter member.

The object of the invention is further to provide a construction in which the fixed cutter member is firmly secured in position in the temple in a simple and efficient manner.

The object of the invention is further to provide a construction in which the fixed cutter member is positively prevented from working loose during the shock and jar to which the temple is subjected in the operation of the loom and in which the proper operative position of the fixed cutter member is thus insured under all conditions.

The nature and objects of the invention will appear more fully from the accompanying description and drawings and will be particularly pointed out in the claims.

30 As the general construction, operation and location of the thread cutting temple in connection with looms are well known and familiar to those skilled in the art, it will only be necessary here to illustrate and describe those features which are particularly concerned with the present invention.

In the drawings:

Fig. 1 is a side elevation of a temple embodying a preferred form of the present invention.

40 Fig. 2 is a view looking at the rearward end of the construction shown in Fig. 1.

Fig. 3 is a top plan view of a preferred form of the fixed cutter member of this in-

vention such as employed in the construction illustrated in Figs. 1 and 2.

Fig. 4 is a view in perspective of the fixed cutter member.

The thread cutting temple of the type illustrated comprises a stand 1, mounted on some fixed part of the loom, such as the breast beam, and a shank 2 which slides yieldingly in the stand and terminates at its rearward end in the head portion where

are located the operative parts of the temple. These temples are located at both sides of the loom and are consequently right and left-handed, the one illustrated being that located at the right hand side of the loom.

The lower portion of the temple head presents the inwardly projecting pod 3 and above and parallel therewith the inwardly projecting cap 4. The cap and pod 3 are separated to allow for the passage of the cloth being woven and in the cap is mounted upon the spindle 5 the usual pin-studded roll.

The cap and pod portions of the temple head are made in separate pieces jointed together at the outer side beyond the line of passage of the cloth. At the forward upper portion of the head this joint between the pod and the cap usually extends substantially horizontal and a screw 7 passed

through the cap and threaded into the pod and having thereon a lock nut 8 is employed to secure the cap and pod rigidly together. A slot 9 extends forwardly and rearwardly through the temple head immediately

adjacent the end of the pin roll 6, and in this slot is located the filling cutting mechanism. This mechanism usually comprises a movable cutter member having a body portion 10, a depending heel 11 and a rearwardly projecting hook-shaped blade or blades 12. A spring 13 coiled at one end about a stud 14 on the temple shank and seated against a shoulder 15 thereon extends downwardly and is coiled at its other end about a stud 16 on the heel 11. This spring acts normally to maintain the movable cutter member in the rearwardly projecting position shown in Fig. 1. Each time the lay beats up, it strikes the heel 11 and thus moves the movable cutter member forwardly and downwardly so that the blade portion is withdrawn into the slot 9.

This movable cutter member cooperates

with a fixed cutter member to effect the severing action of the filling end and it is to this fixed cutter member that the present invention more particularly relates. It is 5 very desirable that the fixed cutter member shall be maintained positively in the required position in the temple head in order that it may cooperate effectively with the movable cutter member.

10 The temple is constantly subjected not only to the general shock and jar of the loom operation, but to the constant, repeated blows of the lay, which not only strikes against the heel 11 of the movable cutter member to effect the cutting action, but also at each beat-up strikes against the heel 17 depending from the temple shank and moves the entire temple forwardly.

In the preferred form of this invention, 20 the fixed cutter member is an integral, one-piece, sheet metal device such as shown in Figs. 3 and 4. It comprises a straight, flat blade portion 18 which normally stands vertically and presents at its rearward portion 25 the cutting edge or edges 19, there being two sets of cutting edges in the present form because two blade portions 12 are shown on the movable cutter member. At its lower end, this blade portion 18 is provided with 30 a depending tongue 20 narrower than the cutting blade so as to present the horizontal shoulder 21. At its upper end the cutting blade 18 is provided with a shank 22 bent at right angles to the plane of the blade and extending forwardly opposite the cutting edge and having its free end 23 lying in a plane normal to the cutting blade 18 and offset laterally therefrom and provided with the aperture 24.

40 The pod 3 of the temple at its rearward portion beneath the slot 9 is provided with a recess 25 fitting the tongue 20.

The fixed cutter blade is so shaped and proportioned that, when it is assembled, the tongue 20 fits in the recess 25, the blade portion 18 stands vertically in the rear end of the slot 9 with its cutting edges in proper position to cooperate with the blades 12 of the movable cutter member, the shank 22 extends along the top of the slot 9 out of the way of the path of the movable cutter member, and the free end 23 of the shank is seated in the joint between the cap and the pod in such a position that the aperture 24 receives the screw 7. When the screw 7 and lock nut 8 are set up, the fixed cutter member is therefore clamped rigidly in place and is positively prevented from working loose under any conditions and is maintained in proper working position at all times.

Having thus described the invention, what is claimed as new, and desired to be secured by Letters Patent, is:

1. A thread cutting temple for looms, 65 comprising a pod and a cap fitted together transversely at the forward portion of the head and presenting a slot extending forwardly and rearwardly therethrough, a movable cutter member mounted to operate 70 in said slot, a vertical, cooperating fixed cutter blade having at its lower end a tongue seated in a recess in the pod beneath, and at the rearward end of, the said slot and having at its upper end a shank extended 75 forwardly and seated between the cap and pod, and means for rigidly securing together the cap, pod and interposed shank.

2. A thread cutting temple for looms, 80 comprising a pod and a cap fitted together transversely at the forward portion of the head and presenting a slot extending forwardly and rearwardly therethrough, a movable cutter member mounted to operate 85 in said slot, a vertical, cooperating fixed cutter blade having at its lower end a tongue seated in a recess in the pod beneath, and at the rearward end of, the said slot and having at its upper end a shank extended 90 forwardly and seated between the cap and pod, and a screw extending through the cap, the said shank and the pod and securing them rigidly together.

3. A thread cutting temple for looms, 95 comprising a pod and a cap fitted together transversely at the forward portion of the head and presenting a slot extending forwardly and rearwardly therethrough, a movable cutter member mounted to operate 100 in said slot, a vertical, cooperating fixed cutter blade, seated at its lower end in the rearward portion of the pod and having at its upper end a shank extended forwardly and seated in the joint between the cap and pod, and means for rigidly securing together the cap, pod and interposed shank.

4. An integral, one-piece, sheet metal cutter member for a thread cutting temple comprising a straight, flat blade having a cutting edge, a tongue at one end of said blade and a shank at the other end of the blade extending opposite the cutting edge and having its free end apertured and lying in a plane normal to the blade.

5. An integral, one-piece, sheet metal cutter member for a thread cutting temple comprising a straight, flat blade having a cutting edge, a tongue at one end of said blade narrower than the blade to present a seating shoulder, a shank at the other end of the blade extending opposite the cutting edge and having its free end apertured and lying in a plane normal to, and laterally offset from, the blade.

In testimony whereof, I have signed my name to this specification.

NEM WILLIAM BRANNON.
